VENDING MACHINE

Adam Ziska, Wauwatosa, Wis., assignor to
Samuel M. Kaufman, Milwaukee, Wis.

Application June 4, 1947, Serial No. 752,382

3 Claims. (Cl. 312—44)

1

This invention relates to improvements in vending machines and more particularly to machines for the vending of a commodity such as ice cream which is packaged in a paper cup.

One of the objects of the present invention is to provide an improved machine wherein a plurality of vertical cup receiving hoppers are mounted on a rotatable spider and wherein there is improved, exteriorly accessible means for causing rotatable movement of said spider to select a predetermined hopper. With this arrangement each hopper may contain ice cream of a different flavor and a selection is thereby made possible.

A further object of the invention is to provide a vending machine, including a hopper in which cups are stacked, wherein there is improved means for controlling the gravity discharge of a cup from the bottom of the stack while positively preventing the discharge of more than one cup at a time.

A more specific object of the invention is to provide in a machine as above described means including a single pull rod cooperable with any one of the hoppers, depending upon which one has been selected by the customer, for actuating the hopper discharge door.

Other objects of the invention are to provide a vending machine which is particularly adapted for the handling of a refrigerated commodity, which is neat in appearance, strong and durable, relatively fool proof, and otherwise well adapted for the purpose described.

With the above and other objects in view the invention consists of the improved vending machine, and all its parts and combinations, as set forth in the claims, and all equivalents thereof.

In the accompanying drawings, illustrating one complete embodiment of the preferred form of the invention, in which the same reference numerals designate the same parts in all of the views:

Fig. 1 is a vertical sectional view of the improved machine taken approximately on the line 1—1 of Fig. 2;

Fig. 2 is a fragmentary sectional view taken approximately on line 2—2 of Fig. 1;

Fig. 3 is a fragmentary plan view illustrating the selector dial and coin slot;

Fig. 4 is a fragmentary detail view on an enlarged scale of the lower end of one of the hoppers looking in the direction indicated by the line 4—4 in Fig. 1, part of the hopper being broken away and shown in vertical section, and the doors being in closed position;

Fig. 5 is a similar view showing the doors in open position and showing the bottommost cup falling through the open door;

Fig. 6 is a sectional view taken on the line 6—6 of Fig. 4 with the cups omitted;

Fig. 7 is a fragmentary vertical sectional view

10 through the coin box and associated mechanism showing a coin in circuit bridging position;

Fig. 8 is a sectional view taken on the line 8—8 of Fig. 7;

Fig. 9 is a detail of one of the contact pin supporting arms;

Fig. 10 is a vertical sectional view through a portion of the dial box illustrating the slot blocking arm and flap;

Fig. 11 is a view taken approximately on the line 11—11 of Fig. 10 showing the flap in a position to prevent the insertion of a coin;

Fig. 12 is a view similar to Fig. 11 showing the flap in its normal position to permit the insertion of a coin;

Fig. 13 is a sectional view taken approximately on the line 13—13 of Fig. 10;

Fig. 14 is an enlarged, fragmentary elevational view of the electric switch and associated parts, part of the switch box being broken away; and

Fig. 15 is an elevational view looking at the hopper feeler arm.

Referring more particularly to the drawing, the improved vending machine may include a cabinet 15 having a removable top 16. Spaced upwardly from the bottom of the cabinet is a horizontal partition 17 separating the interior into a bottom chamber 18 and a main chamber 19. When the vending machine is to be used for a refrigerated commodity, the side walls of the main compartment are lined with a suitable insulating material 20, the cover is lined with a similar material 21, and the partition with insulating material 22.

The partition 17 is formed with an upstanding tubular boss 23 forming a support for the lower end of an upright spindle 24. The partition 17 is also preferably formed with an integral angularly bent discharge chute 25. One end of the discharge chute registers with an opening 26 in the front wall of the cabinet. The other end 27 of the discharge chute faces upwardly and is located in a position to receive merchandise in a manner to be hereinafter described.

The upper end of the spindle 24 is of reduced diameter as at 28. Supported on said reduced portion and rotatable therearound and around the spindle is a sleeve 29. The upper end of the sleeve is closed by a rigidly connected cap 30 having a recess in its lower side which receives a ball-bearing set 31. Rigidly connected to the sleeve at vertically spaced points thereon are spiders 32 and 33 having central openings through which the sleeve extends. The spiders are generally circular in outline and have their peripheries formed with circumferentially spaced circular recesses 34 (see Fig. 2). The spiders are so mounted on the sleeve 29 that the recesses 34 of the top spider are in vertical alinement with the recesses 34 of the bottom spider. Extending

through said alined recesses and suitably connected to the spiders are a plurality of tubular cup holding hoppers 35 open at their upper ends as at 36. These hoppers are generally cylindrical in shape but are open at the peripheries of the spiders as at 37.

Slidably mounted in vertically alined sets of openings 38 and 39 of the spiders are discharge rods 40. There is one discharge rod located inwardly of each cup holding hopper 35. Each discharge rod has an upper collar 41 adjustably mounted thereon which is adapted to engage the underside of the top spider 32 to limit upward movement of the discharge rod. Spaced a substantial distance below the collar 41 is a fixed pin or collar 42. Positioned between each pin or collar 42 and the bottom spider 33 and surrounding the discharge rod is a coil spring 43. The extreme lower end of each discharge rod projects through its opening 39 in the bottom spider 33, and is provided with an inwardly directed lug 44 having an inclined upper surface 45.

Referring now to Figs. 4, 5 and 6, the lower end of each cup holding hopper is equipped with a rigidly connected tubular fitting 46 having apertured ears 47 projecting from opposite sides thereof. Doors 48, each substantially semi-circular in outline, have projecting apertured ears 49. Pivot pins 50 extending through the alined apertures of the ears 47 and 49 hingedly connect the doors to the bottom fitting 46 of each tube, the ears 49 being rigid on the pivot pins 50 to rock therewith.

The pins 50 have mounted loosely thereon sleeves 51. Integral with each sleeve and projecting upwardly from the bottom of the hopper is a cup holding arm 52 having a curved cup-engaging portion 53 at its upper end. Also rigidly connected to each sleeve 51 is an ear 54 which projects laterally outwardly from the hopper. Each ear has a rigidly mounted pin 55. Integral with that ear 49, on each side, which is adjacent the pin 55 is an outwardly projecting lug 56.

When the bottom doors 48 of a hopper are closed as in Fig. 4, the lugs 56 are engaged over the pins 55 as is clear from Fig. 6. As a result, the yielding springs 57 (see Fig. 4) are prevented from moving the cup holding arms 52 inwardly. When the doors 48 are in the open position of Fig. 5, however, then the lugs 56 are swung to a position to release the pins 55. This enables the arms 52 to be urged inwardly by the tension of the band springs 57 into the openings 52' to the position of Fig. 5. During such movement the sleeves 51 on which the arms 52 are mounted are rocked on the shafts 50. The cup-engaging end portions 53 of the arms 52 are thus moved to the position shown in Fig. 5 to form stops which limit downward movement of the shoulder 58 of the cup B of Fig. 4 after said cup has dropped to the position of Fig. 5. In the meantime, the bottom-most cup A has been dropped out of the bottom of the hopper into the discharge chute 25. It is apparent, therefore, that the mechanism just described positively prevents the discharge of more than one cup at a time.

The opening and closing of the bottom doors 48 is under the control of the discharge rods 40. Each rod has rigidly connected thereto a cross-head 59. Pivoted to the ends of the cross-head 59 are the ends of links 60. The other ends of the links 60 are pivotally connected to arms 61 which are rigidly connected to the pivot pins 50. The links 60 pivoted to the crosshead 59 constitute a toggle joint.

As a result of this arrangement, if a pull rod 40 is moved downwardly from the position of Fig. 4, to the position of Fig. 5, it will carry the cross-head 59 downwardly, move the links 60 from the position of Fig. 4 to the substantially vertical position of Fig. 5, and rock the arms 61 and pivot shafts 50 through an arc of approximately 90°. In view of the fact that the door ears 49 are rigidly connected to the pivot pins 50, this will cause opening movement of the bottom doors 48 from the position of Fig. 4 to the open position of Fig. 5 to permit the bottommost cup A to fall out of the hopper as heretofore explained. When the pull rod is released, its spring 43, acting against the collar 42, will return the rod to the raised position, close the doors, and swing the cup holding arms 52 back to the cup-releasing position of Fig. 4. In closed position the crosshead 59 which constitutes the knee of the toggle joint is above center so that the weight of the cups will not tend to open the doors.

Mounted on the front of the cabinet is a dial housing 62. Projecting outwardly and at a slight angle upwardly within the dial housing is a bearing 63 in which a shaft 64 is journaled. The outer end of the shaft 64 projects through the bearing and carries rigidly on its outer end a gear 65 having a dial 66 secured to its outer face. The dial is formed with peripheral slots or recesses 67 at circumferentially spaced intervals. Each slot 67 communicates with the periphery of the dial and is adapted to aline with the open lower end of a coin-receiving slot 68 formed in the dial housing 62. There is one of the peripheral slots 67 for each of the hoppers 36 carried by the rotatable merchandise holding unit within the cabinet. When one of the peripheral slots 67 is in registration with the coin-receiving slot 68 it indicates that its respective hopper is in proper registration with the discharge chute 25, and in proper position for coaction with the discharge mechanism. In addition, each peripheral slot 67 increases the effective length of the coin-receiving slot 63 just enough to permit the reception of a nickel (or other required coin) when one of the peripheral slots is in proper registration. Thus, a coin can only be inserted when one of the hoppers is in a proper position of rotation. The peripheral slots 67 may be labelled to indicate the nature of the merchandise in the respective hoppers. For example, in Fig. 3, "V" indicates that vanilla ice cream is in the cups of those hoppers which correspond to the peripheral slots labelled "V." Similarly, "C" designates chocolate ice cream.

The dial gear 65 is in mesh with a smaller gear 69 and the latter is rigidly mounted on a suitably journaled shaft 70. The outer end of the shaft 70 carried a knurled wheel or knob 71 which may be manually rotated to cause rotation of the selector dial 66.

In order to transmit rotating movement from the dial shaft 64 to the merchandise holding unit it is preferred to utilize a flexible shaft section 72. One end of this shaft section is connected to the inner end of the shaft 64. The other end is rigidly connected to a stud shaft 73 journaled in a bearing 74. The shaft 73 carries a rigidly mounted bevel gear 75 which meshes with a bevel gear 76 rigidly mounted on the spider sleeve 29.

Extending downwardly from the coin-receiving slot 68 and suitably shaped and positioned to avoid the shaft 64 and bearing 63 is a coin chute 77. The upper end of the chute has its opening 78 positioned to register with the coin receiving slot

68. The length of the opening at the upper end of the chute is substantially equal to the combined lengths of the coin-receiving slot 68 and one of the peripheral slots 67. The lower end of the coin chute 77 registers with a suitable slug ejector unit 78 of any well known construction. From the bottom of the slug ejector unit the coin gravitates into a coin chute extension 79. The latter directs the coin downwardly to the position shown in Fig. 7, where it is stopped by spaced contact pins 80. When in this position, the coin 81' bridges the gap between the pins 80 to complete an electrical circuit as will be hereinafter explained. The pins 80 project through horizontal slots 81 and are carried by the lower ends of links 82. The upper ends of the links are pivoted on pins 83. Band springs 84 engaging lugs 85 on the links 82 normally urge the links and pins 80 to the coin-blocking position of Fig. 7. In addition, the springs are adapted to carry electricity from the links 82 and lugs 85 to terminal blocks 86 to which the upper ends of the springs are connected. The blocks 86 and the arms 82 are electrically insulated from the frame. An electric wire 87 extends from one of the terminal blocks to one end of the coil of a solenoid 88 (see Fig. 1). The wire 87 is also connected to a wire 87' leading to a source of electricity. The other end of the coil of the solenoid 88 is connected by a wire 89 with a fixed contact 90 of a normally open switch 91. The other contact of the switch 91 is connected by an electric wire 91' with the source of current and with an electric wire 92 leading to the end of the coil of a solenoid 93. The other end of the coil of the latter solenoid 93 is connected by an electric wire 94 with the other terminal block 86 of Fig. 7.

With this arrangement, when a coin is bridging the pins 80, as in Figs. 1 and 7, an electrical circuit is completed which comprises the wires 87', 87, 94, coil of the solenoid 93, electric wire 92, and portion of wire 91' leading to the source. The energization of the solenoid 93 exerts a downward pull on the core 95. The core is connected to the lower end of a bottom pull rod 96 which extends slidably through the insulating material 22 and partition 17. The upper end of the pull rod 96 is provided with a hook 97 which coacts with the lug 44 on the lower end of one of the upper or hopper discharge rods 40. Below the hook and surrounding the pull rod 96 is a coil spring 98.

Downward movement of the pull rod 96 and hook 97 serves to pull downwardly on the engaged upper discharge rod 40 to open the bottom doors of the adjacent hopper as heretofore explained. During such opening movement the coil spring 98 is compressed. As the core 95 is moved to a fully inserted position in its solenoid it eventually strikes a floating pin 99 which projects from the lower end of the solenoid. This in turn acts on a pin 100 projecting upwardly from the normally open switch 91 to close the switch 91. As soon as the switch 91 is closed a second circuit is completed which comprises the wire 87', coil 88, wire 89, switch 91, and wire 91' leading to the other side of the source.

This energization of the coil 88 causes a downwardly pull on its core 101. The core 101 is, in turn, connected to the lower end of a coin control rod 102. Referring now to Fig. 7, the upper end of the coin control rod 102 is pivoted to the end of a rocker arm 103. The other end of the arm 103 is pivoted to a side of the slug ejector box 78 as at 104. Intermediate the length of the arm 103, the upper end of a pusher rod 105 is pivotally connected as at 106, there being electrical insu-

lating material at 107. The lower end of a push rod 105 rides in a slot 108. As a result of the above construction when the solenoid 88 is energized the push rod 105 will be moved downwardly to push the coin 81' past the contact pins 80 and into the coin receptacle 103. During such movement of the coin, the arms 82 swing outwardly on their pivots 83 against the tension of the flat springs 84. When the coin has fallen through there is no longer any bridging on the pins 80 and the circuit is broken to the solenoid 93. This permits the springs 98 and 43 to return the pull rods 96 and 40 to their elevated positions. Upward movement of the rod 96 causes withdrawal of the core 95 of the solenoid 93 and allows the contacts within the switch box 91 to spring apart breaking the circuit to the other solenoid 88.

Pivotaly mounted within the cabinet adjacent the front wall thereof on a suitably supported pivot 109 is a feeler arm 110 having an inwardly bent vertically elongated portion 111. This portion is adapted to snap into the front openings 31 of the hoppers 36 as said hoppers are brought into and out of registration with the discharge chute 25 upon rotation of the merchandise holding unit. When the hopper 36, which is in registration with the discharge chute 25, still has merchandise therein, the portion 111 of the feeler 110 will be engaged by the top rims of two of the lowermost cups of ice cream. Rigidly connected to the feeler member 110 and projecting from the other side of the pivot 109 is an arm 112.

Referring now to Figs. 10, 11, 12 and 13, if there are still cups in the hopper, a slidable rod 113 will be in the partially withdrawn position of Fig. 12. The outer end of this rod coacts with a leg 114 of a bellcrank lever 115. The latter is pivoted within the dial housing 62 as at 116. The outer end of the bellcrank lever 115 is bent angularly downwardly as at 117 and forms a flap which is movable from the position of Fig. 12 to the position of Fig. 11 to prevent the insertion of a coin into the upper end of the coin chute 77. When there is still merchandise in the hopper which is in registration with the discharge chute 25, the flap will be maintained by the coil spring 118 in the position of Fig. 12 to permit the insertion of a coin.

If an empty hopper, however, is in registration with the discharge chute, then the portion 111 of the feeler 110 will project into the opening 37 of the tube 36, being no longer restrained from such movement by engagement with the ice cream cups. This will cause rocking of the outer end of the arm 112 a short distance in an outward direction to push against the rod 113. This, in turn, pushes the bellcrank 115 to the position of Figs. 10, 11 and 13 to prevent the insertion of a coin. If desired, the flap 117 may have the word "Empty" written thereon to show through the coin-receiving opening 68. Movement of the arm 112 toward an outward position is constantly urged by a suitable spring 119, but such movement is only permitted when the hopper is empty.

65. Intermediate the width of the front wall of the cabinet there may be a vertical opening 120 controlled by a door 121. The door may extend up to the top of the front wall and be hinged as at 122. By opening the door 121 new cups of ice cream or other merchandise may be loaded into the hoppers.

Where a commodity such as ice cream, which requires refrigeration is being handled, the cabinet may be equipped with refrigerating coils

which are indicated schematically at 123. Suitable refrigerating apparatus suitably located in the cabinet may be connected to said coil to cause the circulation of a suitable refrigerant in a well-known manner. For certain types of installations it is entirely satisfactory to insert Dry Ice or some other refrigerant in a container such as the container 124 supported on the cap 30 of the spider. The container may have a removable cover 125 and the top 16 of the main cabinet may also be removable.

Summary of operation

If a person desires to purchase a cupful of ice cream from the machine, assuming that the machine is being used for vending ice cream, it is first necessary to rotate the knob 71 to cause resulting rotation of the selector dial 66 until the slot 67 corresponding to a desired flavor is in registration with the lower end of the coin-receiving slot 68. If there is still merchandise in the selected hopper the flap 117 will be in the position of Fig. 12 to permit insertion of the coin. If the hopper is empty the flap will prevent insertion and the word "Empty" will show through the coin-receiving slot 68. The customer will then know that he must continue turning the knob 71 until a filled hopper is brought into operative position.

After the coin has been inserted it will fall through the chute 77, and if it is a proper coin it will pass through the slug ejector box 78 and into the chute 79 to bridge the electric contact pins 80. As before explained, this will first cause energization of the solenoid 93 and a downward movement of the pull rods 96 and 40 to open the bottom doors 48 of a selected hopper, the parts being in the position of Fig. 5. During such opening movement the arms 52 will move inwardly to the position shown in Fig. 5 to prevent the discharge of more than one cup at a time, as heretofore explained.

Immediately following the discharge of the cup the switch 91 will be closed as heretofore explained, to energize the solenoid 88. This causes a pull on the coin control rod 102, and operation of the push rod 105 to eject the coin into the coin receptacle. As before explained, this will first break the circuit to the solenoid 93. Next, the spring 98 will urge the pull rod 96 and core 95 upwardly to open the switch 91 and break the circuit to the solenoid 88.

It is apparent from the above that the machine makes it possible to quickly select a preferred flavor and obtain the discharge of a cupful of the ice cream. At the same time, due to the reduction gearing between the knob 71 and the dial, the merchandise holding spiders cannot be made to spin fast by tinkering children. The machine provides a simple method of notifying the customer when a particular hopper is empty. In fact, it positively prevents the insertion of a coin when this is the case. The discharge doors, together with the mechanism are so worked out as to insure the proper delivery of a cupful of ice cream in response to the insertion of a proper coin while positively preventing the discharge of more than one cup at a time.

Various changes and modifications may be made without departing from the spirit of the invention, and all of such changes are contemplated as may come within the scope of the claims.

What I claim is:

1. In a vending machine having a cabinet, a vertically disposed cup holding hopper in said

cabinet having side openings, hinge pins supported for rocking movement on opposite sides of said hopper at the lower end thereof, complementary door sections rigidly connected to said hinge pins and projecting inwardly therefrom, lugs connected to said door sections and projecting outwardly from said hinge pins, cup holding arms pivotally mounted on said hinge pins adjacent the side openings of the hopper, yielding means normally urging said arms inwardly into said openings to prevent downward movement by gravity of cups thereabove in the hopper, means on said arms engaged by said door section lugs when the door sections are closed for preventing said inward movement of the cup holding arms, and means for controlling opening and closing movement of said door sections.

2. In a vending machine having a cabinet, a vertically disposed cup holding hopper in said cabinet having a side opening, a hinge pin supported for rocking movement on a side and at the lower end of said hopper, a door rigidly connected to said hinge pin and projecting so as to obstruct the lower end of said hopper, a lug connected to said door and projecting outwardly from said hinge pin, a cup holding arm pivotally mounted on said hinge pin adjacent the side opening of the hopper, yielding means normally urging said arm inwardly into said opening to prevent downward movement by gravity of cups thereabove in the hopper, means on said arm engaged by said door lug when the door is closed for preventing said inward movement of the cup holding arm, and means for controlling opening and closing movement of said door.

3. In a vending machine having a cabinet, a vertically disposed cup-holding hopper in said cabinet having a side opening, a hinge pin supported for rocking movement on a side and at the lower end of said hopper, a door rigidly connected to said hinge pin and projecting so as to obstruct the lower end of said hopper, a cup-holding arm pivotally mounted independently of said door on said hinge pin adjacent the side opening of the hopper, means normally urging said arm inwardly into said opening to prevent downward movement by gravity of cups thereabove in the hopper, a lug on the door engageable with said arm in a manner to move the latter clear of said cups in response to closing movement of said door.
